UNITED STATES PATENT OFFICE.

FRANK LOWER, OF LITTLE ROCK, ARKANSAS, ASSIGNOR OF ONE-HALF TO COLEMAN M. BRADLEY, OF WILLARD, MISSOURI.

MUFFLER.

1,085,276.

Specification of Letters Patent.

Patented Jan. 27, 1914.

Application filed August 14, 1911. Serial No. 643,924.

To all whom it may concern:

Be it known that I, FRANK LOWER, a citizen of the United States, residing at Little Rock, in the county of Pulaski and State of Arkansas, have invented certain new and useful Improvements in Mufflers; and I do hereby declare the following to be a full, clear, and exact description of the invention, such as will enable others skilled in the art 10 to which it appertains to make and use the same.

My invention relates to mufflers for use with internal combustion engines and contemplates an apparatus for reducing the 15 noise and certain other disadvantages incident thereto.

The principal object of my invention is to provide a muffler designed especially for hydrocarbon engines having means for reducing the back-pressure produced therein, which is caused by the expansion of the hot 20 gases as they escape from the cylinder of the engine.

Another object of my invention is to provide, in combination with the muffler, a means for cooling the burned products of combustion, as well as the muffler.

Another object of my invention is to provide a means combined with the muffler for 30 aiding in the expulsion of the wasted gases therefrom, thereby preventing the gases from being backed up in the muffler and choking the exhaust valves and conduits.

Figure 1 is a side elevation of my improved muffler; Fig. 2 is a central vertical sectional view of my invention illustrating the arrangement of the exhausting fans relative to the muffler casing; Fig. 3 is a sectional view taken on the line 3—3 of Fig. 1, 40 and showing the construction of the primary exhausting and pressure reducing fan, and Fig. 4 is a sectional view taken on the line 4—4 of Fig. 1 illustrating the construction of the other exhausting secondary fan.

Referring now to the drawings by numerals of reference, representing corresponding parts throughout the several figures, 1 indicates a muffler comprising a cylindrical casing having secured at the lower 45 end thereof, by rivets or other fastening means 1', a closing head 2 provided with a centrally located opening 3 to receive one end of nipple 4 which conducts the burned gases into the muffler from the exhaust pipe 4' leading from the cylinder of a gas engine

(not shown). Surrounding the said cylindrical muffler casing 1 and concentric therewith is a water jacket 5 consisting of a cylindrical shell or casing 6 having at the lower end thereof, a head or closure 7 also provided with a centrally arranged opening 8 in alignment with the said opening 3 in the head of the member 1, to receive the other end of the nipple 4, whereby the said gases are conveyed through the space of channel 9 which received the cooling water. Suitable fastening means for either end of the nipple 4 are provided, the same consisting of washers or nuts 10 and 10', the latter being further secured by a lock nut 11. A feed pipe 12 leads to the lower portion of the water jacket 5 for supplying cold water thereto, while an outlet pipe 12' leads from the upper portion of said water jacket for drawing off the water after it has become heated by contact with the walls of the muffler 1.

Arranged within the upper portion of the casing 6 and secured to the top of the muffler 1 is a primary centrifugal fan 14, inclosed within a casing 15, the lower portion of the latter constituting a closure 16 for that end of the said muffler to which it is attached, said closure 16 being provided with a centrally arranged opening 17 through which the hot gases escape from the muffler into the path of the vanes or blades of said fan, said opening 17 being provided with a raised bridge 18 forming the bearing for one end of the arbor or spindle 19 passing through and supporting the hub of the fan 14. The other end of the arbor or spindle is suitably journaled in the casing 15. The fan casing 15 is provided with an opening 21 in the periphery thereof from which leads a conduit 22 adapted to carry the gases thrown by centrifugal force of the fan 14, from the casing 15 into the path of rotation of a secondary fan 23. This fan 23 is inclosed in a casing 24, similar in character and design to the casing already mentioned, consisting of separable shells secured together by rivets or other suitable fastening means 24', a portion of which casing constitutes the closing head for the other end of the cylindrical shell or casing 6, and said closing head having an opening 26 therein leading from the conduit 22 to the fan chamber 24. The fan 23 is mounted upon a hub 25 through which passes the arbor or spindle 19, a single shaft serving the purpose of securing both fans, 114

whereby said fans 14 and 23 are rotated simultaneously through the medium of suitable driving power transmitted to the arbor or spindle by a pulley or sprocket wheel 27 and belt or chain 28. The fan chamber 24 is provided with an outlet 29 to conduct the gases of combustion to the atmosphere. A suitable pump 30 may be included in the water cooling system to promote the more thorough circulation of the cooling water therethrough.

The operation of my invention is as follows: The gases of combustion escape from the cylinder of the gas engine, passing through pipe 4' and nipple 4 into the muffler 1, where coming into contact with the water cooled walls thereof, they are contracted causing a partial vacuum. I have provided centrifugal fans which, rotating at a suitable determined rate of speed, cause the contracted gases to be sucked into their respective chambers successively. The first or primary fan 14 takes up the exhaust charge and by centrifugal force throws it into the conduit or channel 22 from whence it passes to the secondary fan 23, said fan 14 at the same time further reducing the pressure within the muffler 1 so that the following exhaust charge from the engine will not be obstructed in its passage thereto. By the time the gases have reached the secondary fan 23, they will have substantially been reduced to their minimum degree of contraction, and the pressure having been reduced and practically eliminated, the function of the fan 23 will be simply to expel the gases through the outlet 28 by centrifugal force into the atmosphere, noiselessly and in a cooled condition. The primary fan 14 is water cooled preventing excessive heating thereof and further materially cooling the gases of combustion before they are allowed to enter the secondary fan.

It is obvious that various changes may be made in the construction of my apparatus,

within the scope of the following claims which form a part of this specification, and to all such modifications and changes I extend my claim and desire protection.

Having thus fully described this invention, what I claim as new and desire to secure by Letters Patent is:

1. A muffler comprising in combination, a muffler casing a water jacket casing surrounding the muffler casing and concentric therewith, means for closing one end of the muffler casing and the water jacket casing, a primary centrifugal fan within the water jacket casing, means for inclosing said fan and supporting the same within the muffler casing, a secondary centrifugal fan supported upon the water jacket casing, a casing for said secondary fan, an arbor or spindle passing through the axis of each fan to provide a bearing therefor, and means of communication between the first and second named fan chambers.

2. A device of the class set forth, comprising a muffler casing, a water jacket casing surrounding said muffler casing and providing a water circulating channel, means for causing the circulation of water through said channel, a nipple passing through said channel and connected at each end with the water jacket casing and the muffler casing respectively, a water cooled fan supported for rotation upon said muffler casing within the water jacket casing, a chamber inclosing said fan, a second fan mounted for rotation upon the top of the water jacket casing, a chamber inclosing said fan, a conduit connecting the two named fan chambers, and an outlet connected and leading from the second named fan chamber.

In testimony whereof I affix my signature in presence of two witnesses.

FRANK LOWER.
